UNITED STATES PATENT OFFICE.

DAVID M. FOWLER, OF DANVILLE, ILLINOIS.

CHANGE-DELIVERY DEVICE.

No. 921,219.

Specification of Letters Patent.

Patented May 11, 1909.

Application filed September 21, 1908. Serial No. 453,923.

To all whom it may concern:

Be it known that I, DAVID M. FOWLER, a citizen of the United States, residing at Danville, in the county of Vermilion and 5 State of Illinois, have invented a new and useful Change-Delivery Device, of which the following is a specification.

This invention has reference to improvements in change delivery devices and is 10 designed to deliver to the operator any sum of money desired on the manipulation of a suitable key or button.

The invention is designed to facilitate the making of change by causing the delivery 15 at a suitable point of any amount of change desired in coin by providing a number of coin receptacles from the lowest to the highest denomination for which any particular machine may be built and these receptacles are provided with delivery mechanisms connected singly and in multiples to various levers or keys which latter will be provided with proper designations so that 20 on the manipulation of any proper key, one or more of the coin receptacles will be operated to deliver the respective coins to make up the sum desired.

The invention will be best understood from a consideration of the following detail 30 description taken in connection with the accompanying drawings forming a part of this specification, in which drawings,

Figure 1 is a plan view of the machine with parts in section and the casing omitted. 35 Fig. 2 is a longitudinal vertical section on the line A—B of Fig. 1. Figs. 3, 4 and 5 are detail perspective views on a larger scale than shown in Figs. 1 and 2.

Referring to the drawings there is shown 40 a number of receptacles 1 in the form of cylinders of suitable size to receive stacks of coins of different denominations. In the particular arrangement shown in Fig. 1 there is shown at the left-hand end of the 45 figure a receptacle adapted to receive a stack of dollar coins, the next receptacle in order toward the right is intended to receive a stack of half dollars, and the next quarter dollars, and the next two receptacles are each provided for holding ten cent pieces or 50 dimes and the remaining two receptacles are designed to hold five cent pieces and one cent pieces in the order named. The particular number of receptacles noted is to be

taken illustratively only since this number 55 may be larger or smaller or be arranged for other coins than those named, as may be desired.

The receptacles 1 are mounted in a row upon a horizontal bar 2 supported at the 60 ends in sides 3 of the frame of the machine. Coincident with each receptacle 1, which latter is secured upon the bar 2, the latter has a perforation 4 of a size sufficient to permit the passage of a coin of the size for 65 which the receptacle is designed.

Extending along the under face of the bar 2 is another bar 5 having recesses 6 formed across its upper face, there being a recess for each receptacle 1 and the recesses are of 70 widths corresponding to the sizes of the receptacles. Extending through each recess 6 is a slide 7 movable in a direction to traverse the bar 5 within the recess 6 and each slide 7 is held in a position whereby a passage 8 through the slide is normally held coincident with the passage 4 through the bar 2 by means of a spring 9 connected to the rear end of the slide at one end and at 75 the other to a rod 10 extending across the 80 machine and secured at its ends to the main frame of the said machine. The movement of the slide 7 under the action of the spring 9 is restricted by a bracket 11 individual to each slide. These brackets are made fast to 85 a bar 12 extending across the frame of the machine below the bar 2 and the upper or free end of each bracket is formed with a recess 13 to permit the passage of the spring 9 when extended.

Fast in the sides of the main frame 3 is a rod 14 extending across the frame at a considerable distance below the bar 2. This rod 14 serves as a journal support for a number of arms or levers 15 spaced on the 95 rod 14 by means of spacing sleeves 16 and these levers or rock arms 15 are so spaced as to be in front of a respective receptacle 1, there being as many rock arms 15 as there are receptacles 1. Each rock arm at its 100 upper or free end is connected to a respective slide 7 by means of a link 17 so that when a rock arm 15 is moved about the rod 14 as an axis in a direction away from the receptacles 1 the corresponding slide 7 will participate 105 in such movement against the action of the spring 9, and when the rock arm 15 is relieved from its actuating force then the

spring 9 will return the parts to normal position wherein the slide 7 is located beneath the corresponding receptacle 1 with its passage 8 coincident with the passage 4 through 5 the bar 2.

Journalized in the side members of the frame 3 are a number of rock shafts 18 arranged in a number of staggered series, and in the particular structure shown in the 10 drawings there are three such series one above another and the individual members of the series being in staggered relation from the front toward the rear. Each rock shaft 18 carries one or more arms 19 and 15 certain of these arms are connected by strands 20 to a corresponding one of the rock arms or levers 15 mounted on the rod 14. The strands 20 are indicated in the drawings as being made of chains, but it 20 will be understood that any other flexible strand may be used although chains are to be preferred. The purpose of using flexible strands will appear hereinafter. At 25 the front of the frame 3 are a number of rods 21 each carrying a number of angle or bell crank levers 22 in spaced relation one to the other and these levers 22 may be spaced upon the rods 21 in the same manner as the levers 15 are spaced upon the rod 14.

30 In the particular structure shown in the drawings, there are three rods 21 one above the other and each rod carries a certain number of bell crank levers 22. One arm of each lever 22 is connected by a link 23 to 35 one of the arms 19 on a shaft 18 or by a chain 24 directly to one of the rock arms 15. In the particular structure shown there are seven receptacles 1 and seven rock arms 15, and seven of the bell crank levers 22 are 40 directly connected to respective ones of the rock arms 15. The other bell crank levers 22 are connected each to a respective one of the rock shafts 18 by means of a link 23 and a corresponding rock arm 19. Each rock 45 shaft 18 has arms 19 other than those connected to the bell crank levers 22 and these arms are connected each to one of the rock arms 15 and through the latter to a slide 7. Each rock shaft 18 is connected to two or 50 more slides 7 depending upon the amount of change called for by the particular bell crank lever 22. In order to operate a bell crank lever 22 it is engaged by the stem 25 of a push key 26 and these keys are exposed 55 exterior to a suitable casing 27 provided for inclosing the working parts of the machine. In the particular instance shown these keys are illustrated as extending up through the top of the casing and being arranged in convenient positions for operation. Of course 60 the ends of the levers 22 may be carried out through the front of the casing and be there provided with manipulating keys as is common in machines of this character. For this 65 reason the invention is not at all limited to

any particular means for operating the levers 22 and the means shown are to be taken simply as illustrative. Each key 26 will have displayed on it a character indicating the amount of change which will be 70 delivered on the depressing of the key.

Since certain of the bell crank levers 22 are connected directly to the slide 7 through the arms 15, the push buttons controlling these levers will have designations corresponding to the coins within the respective receptacles. The other keys with other designations thereon and controlling other levers 22 will be connected by said levers to certain ones of the shafts 18 and these shafts 80 will have an appropriate number of rock arms 19 connected to appropriate rock levers 15 to cause the actuation of a sufficient number of the slides 7 to deliver the desired number of coins to make up the amount called 85 for. For instance if thirty cents change be desired, then the key marked 30 will control a bell crank lever 22 which is connected to a shaft 18 having arms 19 in turn connected to the rock levers 15 which control the slides 90 of the receptacles containing the twenty-five cent pieces and five cent pieces and these two slides will be moved simultaneously when the particular key is depressed, so that two coins, the total value of which is thirty cents, 95 are delivered at the same time. As another example let it be assumed that ninety-five cents is the desired amount of change. Then one of the shafts 18 will have its arms 19 connected up to the rock arms or levers 15 100 coupled to the slides of the receptacles containing the fifty cent pieces, the twenty-five cent pieces, and the two receptacles each containing ten cent pieces. So the various parts of the machine are coupled up to different 105 coin receptacles to cause the delivery of the desired amount and change by any amount differing by five cents may be obtained from the machine on the manipulation of the proper keys, a single key delivering the desired amount of change instead of there being a necessity of depressing more than one key when it is desired to obtain amounts of money differing from the amounts contained 110 in any one receptacle. 115

In order to facilitate the introduction of stacks of coins into the receptacles a portion of each receptacle may be made separate from the fixed portion of the receptacle and hinged thereto as indicated at 28 in Fig. 3, 120 and suitable catches 29 are provided for locking the hinged portion of the receptacle to the main body thereof in such a manner as to hold the stack of coins therein but still not prevent access to the receptacle. The 125 slides 7 are made thinner than the normal thickness of the coins controlled thereby so that in the event of a worn coin being in the stack the slide will still be no thicker than such worn coin and thereby the hanging of 130

the slide on the next coin above is prevented. By interposing flexible strands 20 between the arms 19 and the rock levers 15, each shaft 18 becomes independent of the other shafts, even though several of the shafts 18 may have connections with the same rock lever 15.

The casing 27 may be provided with a suitable drawer 30 for holding bills or other moneys, and where the casing 27 is made to inclose the receptacles 1 a transparent panel 31 may be provided in front of the said receptacles and the latter are each formed at the front with a longitudinal slot 32 so that the operator may readily observe the amount of coin in each receptacle and thereby become aware of the depletion of the receptacle so that they may be replenished in ample time. Beneath the bar 5 there is provided a suitable chute into which coins removed from the receptacles by the slides 7 may gravitate and so be delivered to the outside of the casing. In Fig. 2 this chute is indicated at 33, but it will be understood that this showing is indicative only and not to be taken as an exact showing of the structure.

What is claimed is:—

1. In a device of the character described, a series of coin receptacles, slides coacting therewith for delivering one coin at a time, key levers, rock levers equal in number to the coin receptacles, flexible strands each connected at one end to a predetermined one of the key levers and at the other end to one of the rock levers connected to the coin delivery devices, and other connections between other predetermined ones of the key levers and predetermined groups of the said rock levers, those portions of the said last named connections leading to groups of the rock levers being flexible.

2. In a device of the character described, a series of coin receptacles, coin delivering slides coacting with the receptacles, and equal in number thereto, a series of rock levers, one for each coin delivering slide, rock shafts each having a plurality of rock arms thereon, flexible connection between the arms on the rock shafts and the rock levers connected to the coin slides, key levers

and connections between the rock shafts and predetermined ones of the key levers.

3. In a device of the character described, a series of coin receptacles, coin slides equal in number to the receptacles for delivering coins one at a time therefrom, rock levers connected to the coin slides, one rock lever for each coin slide, rock shafts having rock arms thereon, flexible connections between the rock arms and the rock levers connected to the coin slides, key levers, flexible connections from predetermined ones of the key levers and the rock levers connected to the coin slides and connections from others of the key levers to the rock shafts.

4. In a device of the character described, a series of receptacles for coins, a coin delivering slide for each receptacle and arranged to deliver one coin at a time, a series of rock levers, one for each coin slide and connected thereto, a series of key levers and flexible connections therefrom directly to the rock levers, intermediate rock shafts and flexible connections therefrom to the rock levers, and other key levers connected to the rock shafts.

5. In a device of the character described, a series of coin receptacles, a delivery slide coacting with each receptacle, a spring for each delivery slide acting to normally hold the same in coin-receiving relation to its respective receptacle, a rock lever for each coin slide and connected thereto, key levers, direct flexible connections between predetermined ones of the key levers and the rock levers, rock shafts each provided with rock arms, flexible connections between predetermined ones of the rock arms and the rock levers, and connections between the key levers not directly connected with the rock levers and said rock shafts.

In testimony that I claim the foregoing as my own, I have hereto affixed my signature in the presence of two witnesses.

DAVID M. FOWLER.
